RAZOR BLADE PACK

Leopold Kuhnl, Bridgeport, and John R. Reyburn, Fairfield, Conn., assignors to Magazine Repeating Razor Company, New York, N. Y., a corporation of New Jersey

Application September 11, 1941, Serial No. 410,406

12 Claims. (CL. 206—16)

The invention relates to razors of the magazine type and particularly to a blade pack that may be utilized for loading the magazine.

The object is a blade pack the blades of which are retained in assembly by a suitable clip which may co-operate with the moving parts of the razor to insert the pack in the magazine and which may be stripped from the stack after insertion of the pack by simply retracting the blade feeding plunger.

Another object is a blade pack of the nature just described in which, while the clip can be readily stripped from the stack of blades, the blades are nevertheless retained securely against dislocation by shipping and handling and the operation of loading the magazine.

Another object is a blade pack of the same character as already described, in which the cutting edges of the blades are protected against impairment by contact with the walls of the magazine and other objects.

Referring to the drawing,

Fig. 1 is a view in longitudinal-vertical section of a razor in connection with which the blade pack may be used, and showing a stack of blades therein ready for ejection one by one to the shaving head of a razor;

Fig. 2 is an isometric view of the blade pack inverted from the position shown in Fig. 1;

Fig. 3 is an isometric view of the blade pack reversed in position from the position shown in Fig. 2;

Fig. 4 is a longitudinal-vertical section on the median plane of the razor pack of Fig. 2;

Fig. 5 is a view in section on the line 5—5 of Fig. 4;

Fig. 6 is a detail view showing how the main spring of the razor co-operates with the blade pack;

Fig. 7 is an isometric view of a single blade of the pack partly broken away;

Fig. 8 is an isometric view of a modified form of clip by which the blade pack is retained in assembly;

Fig. 9 is a view of the handle of a razor showing how the blade pack may be inserted therein.

Referring more in detail to the drawing, the blade pack itself will first be described. It consists, in the first place, of a stack of blades, a single one of which (10) is illustrated in Fig. 7. In this case it is of the "single cutting edge" type and is provided with indentations 11 and 11a on one face and protuberances 12 and 12a on the opposite face. The indentations may be produced by punching, which at the same time forms the

nubs so that to each indentation there is a nub on the opposite side of the blade similarly positioned longitudinally and laterally of the latter. The blades may therefore be stacked so that the nubs of each blade nest in and engage mating indentations in a contiguous blade, and thus the stack takes the form of a rectangular parallelepipedon with the edges of the blades all on one side. For convenience in the punching operation and to adapt the indentations and nubs for co-engagement, the contour of each indentation approximately conforms to that of the surface of a cone, thus in each case producing shoulders 13 and 13a. The nubs are of a contour similar to that of the indentations and thus there are produced shoulders 14 and 14a. In stacking, shoulders 14 and 14a of the nubs abut the shoulders 13 and 13a of the indentations of a contiguous blade, the nubs nesting in the indentations. Both indentations and nubs slope away from the surface of the blade in the same direction with respect to the blade. The slope of the indentations and the slope of the nubs are such that each blade can be dislodged from the blade beneath it (with reference to the position shown in Fig. 1) by the application of a force acting longitudinally of the blade in a direction to separate the abutting shoulders. A blade cannot, however, be dislodged from its neighbor by the application of a longitudinally acting force in the opposite direction due to the positive resistance offered by the abutting shoulders of the indentations and nubs.

The stack indicated by the numeral 15 is retained in assembly by means of a clip having the general form of the letter "U" and comprising two legs 16 and 17 formed by folding a strip of sheet metal on itself so that the legs are approximately parallel with each other or, preferably, slightly convergent from the fold 33. The metal of the clip is resilient to render the clip readily releasable but at the same time it is stiff enough to clamp the stack firmly. The leg 17 may extend the entire length of the stack, but the leg 16 is short enough to expose the shoulder 14 of the nub 12 of the upper exterior blade (with reference to the position shown in Fig. 2) and is provided with an aperture 18 which engages the nub 12a of the same blade. This engagement consists in releasably locking the clip to the stack, but by virtue of the slope of the nub and the corresponding slope of the indentation with which it is engaged does not interfere with the withdrawal of the clip from the stack. The marginal areas of both legs extend beyond the plane of the blade cutting edges and are deflected to

ward each other as shown at 19 and 19a so that they slope over the facets of the exterior blades of the stack. The opposite marginal areas of the legs are turned toward each other at approximately right angles as shown at 20 and 20a. The extension of these marginal areas 19 and 19a beyond the cutting edges of the blades of the stack protects the cutting edges from injury in handling and in inserting into the magazine as will presently appear. The inturned portions 20 and 20a positively prevent dislocation of the blades of the stack in their direction. Dislocation of the blades of the stack in the opposite direction is prevented by the inturned portions 19 and 19a. In explanation, it is to be noted that in the sharpening operation most razor blades are first ground so that the bevel facets resulting from grinding include a predetermined included angle. In honing this included angle is increased near the extreme edge. Where this is the case the deflection is such that the deflected portions may, and preferably are, in contact throughout with the ground areas of the bevel facets. In this relationship, however, they are clear of the honed areas and of the cutting edges by reason of the increased angle referred to. However, it is not necessary that the inturned portions 19 and 19a lie in contact with the ground areas of the facets throughout. It is sufficient if they are inturned enough to serve as a barrier to the dislocation of the stack in their direction. In either case the pack may be handled and shipped and inserted in a razor as will be later explained without impairing the sharpness of the edges.

To avoid dislocation of the stack in the direction of the fold of the clip, ears 21 and 22 may be struck in, the ear 21 from the shorter leg 16 and the ear 22 from the longer leg 17. As a matter of practice, only one of these ears is necessary, and, if only one is made use of, it is preferably the ear 22, since in the process of striking it in, the aperture 23 is produced, the purpose of which will presently appear in connection with the description of the razor in which the pack is to be inserted. For further security the tabs 23a and 23b may be struck from the edges of the legs 16 and 17. Contact of the extreme ends of the edges of the blades with these tabs does no harm since the razors in which such blades are used are nearly always provided with means to protect the face of the user from being cut or scratched by the extreme corners of the blades.

A modified form of clip with the stack shown in dotted lines is shown in Fig. 8. It is similar to the clip already described except that the inturned tabs 24 and 24a serve the purpose of the inturned edge 19a and the inturned tabs 25 and 25a serve the purpose of the inturned edge 19 (see Fig. 5). The angles of deflection of these tabs are the same as the angles of deflection of the edges 19 and 19a of Fig. 5. The modification consists in merely removing functionless material from the clip.

Likewise, the clip of Fig. 8 is provided with tabs 26 which take the place of the inturned edges 20 and 20a of Fig. 5. In this case also the modification consists merely in removing functionless material from the inturned portions 20 and 20a of Fig. 5.

Before describing the way in which the invention may be utilized, it may be pointed out that, if the shoulder of the nub 12 of the upper exterior blade (Fig. 2) engages a positive stop acting against the shoulder 14, the clip may be

stripped from the stack in a lengthwise direction without disturbing the stack assembly since each blade beginning with the topmost blade (also Fig. 2) positively engages the blade succeeding it by virtue of the inter-engagement of the shoulders of the nubs and indentations.

Proceeding then to a description of a suitable razor with which the pack may be used and as an illustration of how it may be used, reference is made to Fig. 9. In this figure the shaving head of the razor is omitted since insofar as the purposes of the invention are concerned it is immaterial what becomes of a blade as it is ejected from the magazine. In Fig. 9 therefore is shown only the handle of a razor which, besides serving as a handle, also serves as a magazine for blades. A razor of this general type having the characteristics given is shown in patents to Schick, No. 1,797,733, issued March 24, 1931; Rodrigues, No. 2,111,739, issued March 22, 1938; and Rodrigues, 1,877,429, issued September 13, 1932, the essential characteristics of which, except so far as adapted to utilize the blade stack of this invention, consists of an elongated boxlike structure 21, provided with a reciprocably mounted plunger for ejecting the blades from the magazine one by one through the blade-ejection orifice 28 and a main spring 29 for causing the stack, as a whole, to bear against a wall of the structure. The plunger, indicated by the numeral 30, is provided with a closure block 31 which, when occupying the position shown in Fig. 1, closes the open end of the structure. The plunger is provided with a hook 32 with which the aperture 23 detachably engages. The stack having been laid on the plunger as shown in Fig. 9 and with the aperture 23 in engagement with the hook, the pack may be driven into the magazine by virtue of the fact that the folded portion 33 of the clip abuts the closure piece 31. As the pack proceeds inwardly it rides under the spring 29 and deflects it and, as the nub 12 passes the tip 34 of the spring 29, it positively engages the shoulder 14 of the nub. While thus engaged, withdrawal of the stack is positively prevented, although the clip may be readily stripped from it, and this is accomplished by simply withdrawing the plunger by grasping the closure block, the clip being withdrawn by virtue of its engagement with the hook 32 leaving the stack in the position shown in Fig. 1. The tip of the spring 29 may be forked as shown in Fig. 6 in order to prevent lateral dislocation of the stack and thus prevent contacting of the blade edges with the wall of the magazine. When fully withdrawn, the clip may be readily detached from its engagement with the hook 32 and discarded.

While we have described a certain particular construction in which our invention is incorporated, we do not desire to be limited to this particular embodiment since many changes and modifications may easily be made without departing from the spirit and scope of the invention as set forth in the following claims.

We claim:

1. A razor blade pack comprising a stack of razor blades and a U-shaped clip retaining the stack in assembly, at least one of the legs of the clip being provided with a flange closely overlying and sloping over an exposed bevel facet of one of the exterior blades of the stack to prevent lateral movement of the stack in the direction of said flange, and an abutment on one of said legs for resisting lateral movement of said stack away from said flange, the location of said abut-

ment on said leg being on the edge thereof that is remote from the side of the pack where the said flange is located.

2. A razor blade pack comprising a stack of razor blades and a U-shaped clip retaining the stack in assembly, at least one of the legs of the clip being provided with a flange closely overlying and sloping over an exposed bevel facet of one of the exterior blades of the stack to prevent lateral movement of the stack in the direction of said flange, an abutment on one of said legs for resisting lateral movement of said stack away from said flange, the location of said abutment on said leg being on the edge thereof that is remote from the side of the pack where the said flange is located, and another abutment on one of said legs for resisting longitudinal movement of said stack in the direction of the base of the clip.

3. A razor blade pack comprising a stack of razor blades and a U-shaped clip retaining the stack in assembly, at least one of the legs of the clip being provided with a flange closely overlying and sloping over an exposed bevel facet of one of the exterior blades of the stack to prevent lateral movement of the stack in the direction of said flange, one of said legs being provided with an abutment for resisting lateral movement of said stack away from said flange, the location of said abutment on said leg being on the edge thereof that is remote from the side of the pack wherein said flange is located, said clip being provided with an aperture in the region of its base serving as a means whereby it may be stripped from said stack.

4. A razor blade pack comprising a stack of razor blades and a U-shaped clip of resilient material clamping the stack in assembly under resilient pressure, the legs of the clip being provided with flanges closely overlying and sloping over the bevel facets of the exterior blades of the stack to prevent lateral movement of the stack in the direction of said flange, and an abutment on at least one of said legs positioned at an edge thereof remote from said flanges for resisting lateral movement of said stack away from said flange and also an abutment on one of said legs positioned near the bend of the U for opposing longitudinal movement of said stack in the direction of the U.

5. A razor blade pack comprising a stack of razor blades and a U-shaped clip retaining the stack in assembly, each blade being provided with a nub on one face and an indentation on the other, the nub of each blade being nested in the indentation of a contiguous blade, at least one of the legs of the clip being provided with a flange closely overlying and sloping over an exposed bevel facet of one of the exterior blades of the stack to prevent lateral movement of the stack in the direction of said flange, and an abutment on one of said legs for resisting lateral movement of said stack away from said flange, the location of said abutment on said leg being on the edge thereof that is remote from the side of the pack where said flange is located.

6. A razor blade pack comprising a stack of razor blades and a U-shaped clip retaining the stack in assembly, each blade being provided with a nub on one face and an indentation on the other, the nub of each blade being nested in the indentation of a contiguous blade, at least one of the legs of the clip being provided with a flange overlying and sloping over an exposed bevel facet

of one of the exterior blades of the stack, an abutment on one of said legs positioned on an edge thereof opposite said flange for resisting lateral movement of said stack away from said flange and another abutment on one of said legs positioned near the bend of the U for resisting longitudinal movement of said stack in the direction of the said bend, the leg contiguous to the exterior blade from which a nub projects outwardly being sufficiently short to expose the nub.

5 7. A razor blade pack comprising a stack of razor blades and a U-shaped clip of resilient material retaining the stack in assembly under resilient pressure, each blade being provided with 15 a nub on one face and an indentation on the other, the nub of each blade being nested in the indentation of a contiguous blade, at least one of the legs of the clip being provided with a flange closely overlying and sloping over an exposed bevel facet of one of the exterior blades of the stack to prevent lateral movement of the stack in the direction of said flange, and an abutment on one of said legs positioned at an edge thereof remote from said flange for resisting lateral movement of said stack away from said flange.

20 8. A razor blade pack comprising a stack of razor blades and a U-shaped clip retaining the stack in assembly, each blade being provided with a nub on one face and an indentation on the other, the nub of each blade being nested in the 30 indentation of a contiguous blade, at least one of the legs of the clip being provided with a flange closely overlying and sloping over an exposed bevel facet of one of the exterior blades of the stack to prevent lateral movement of the stack in the direction of said flange, one of said legs being provided with an abutment positioned at an edge thereof remote from said flange for resisting lateral movement of said stack away from said flange, said clip being provided with an aperture in the region of its base serving as a means whereby it may be stripped from said stack.

35 9. A razor blade pack comprising a stack of razor blades and a U-shaped clip of resilient material clamping the stack in assembly under resilient pressure, each blade being provided with a nub on one face and an indentation on the other, the nub of each blade being nested in the 40 indentation of a contiguous blade, the legs of the clip being provided with flanges sloping over the facets of the exterior blades, and an abutment on at least one of said legs positioned at an edge thereof remote from said flanges for resisting lateral movement of said stack away from said flanges and also an abutment on one of said legs positioned near the bend of the clip to oppose longitudinal movement of said stack in the direction of the said bend, the leg contiguous to the exterior blade from which a nub projects outwardly being sufficiently short to expose the nub.

45 10. A razor blade pack comprising a stack of razor blades and a U-shaped clip retaining the stack in assembly, each blade being provided with a nub on one face and an indentation on the other, the nub of each blade being nested in the 55 indentation of a contiguous blade, the nub and indentation sloping away from the surface of the blade and toward one end thereof at an angle small enough so that a blade may by an endwise sliding motion be dislodged from the blade contiguous to it, at least one of the legs of the clip being provided with a flange closely overlying and sloping over an exposed bevel facet of one of the exterior blades of the stack to prevent lateral

movement of the stack in the direction of said flange, and an abutment on one of said legs positioned at an edge thereof remote from said flange for resisting lateral movement of said stack away from said flange.

11. A razor blade pack comprising a stack of razor blades and a U-shaped clip retaining the stack in assembly, each blade being provided with a nub on one face and an indentation on the other, the nub of each blade being nested in the indentation of a contiguous blade, the nub and indentation sloping away from the surface of the blade and toward one end thereof at an angle small enough so that a blade may by an endwise sliding motion be dislodged from the blade contiguous to it, at least one of the legs of the clip being provided with a flange overlying and sloping over an exposed facet of one of the exterior blades of the stack, an abutment on one of said legs positioned at an edge thereof remote from said flange for resisting lateral movement of said stack away from said flange and another abutment on one of said legs positioned near the base of the clip for resisting longitudinal movement of said stack in the direction of the said base, the leg contiguous to the exterior blade from which

25 a nub projects outwardly being sufficiently short to expose the nub.

12. A razor blade pack comprising a stack of razor blades and a U-shaped clip retaining the stack in assembly, each blade being provided with a nub on one face and an indentation on the other, the nub of each blade being nested in the indentation of a contiguous blade, the nub and indentation sloping away from the surface of the blade and toward one end thereof at an angle small enough so that a blade may by an endwise sliding motion be dislodged from the blade contiguous to it, at least one of the legs of the clip being provided with a flange closely overlying and sloping over an exposed bevel facet of one of the exterior blades of the stack to prevent lateral movement of the stack in the direction of said flange, one of said legs being provided with an abutment positioned at an edge thereof remote from said flange for resisting lateral movement of said stack away from said flange, said clip being provided with an aperture in the region of its base serving as a means whereby it may be stripped from said stack.

LEOPOLD KUHN, JOHN R. REYBURN.
